Paul Paul,

UNITED STATES PATENT OFFICE.

LE ROY O. HENDRICKS, OF MINNEAPOLIS, MINNESOTA.

LUGGAGE-CARRIER.

1,205,741.

Specification of Letters Patent. Patented Nov. 21, 1916.

Application filed December 2, 1915. Serial No. 64,672.

To all whom it may concern:

Be it known that I, LE ROY O. HENDRICKS, citizen of the United States, resident of Minneapolis, county of Hennepin, State of Minnesota, have invented certain new and useful Improvements in Luggage-Carriers, of which the following is a specification.

The object of my invention is to provide a carrier having means for mounting it on the running-board of an automobile and adapted for supporting suit cases, steamer trunks, and the like.

A further object is to provide a carrier which can be easily increased or decreased in size to adapt it for the varying shape or size of pieces of luggage.

A further object is to provide a carrier which can be easily and quickly mounted on a running board and as readily removed therefrom.

The invention consists generally in various constructions and combinations, all as hereinafter described and particularly pointed out in the claims.

In the accompanying drawings forming part of this specification, Figure 1 is a perspective view of a portion of the running board and body of an automobile, with my invention applied thereto, Fig. 2 is a plan view of the carrier shown in its closed or folded position in full lines and its extended position in dotted lines, Fig. 3 is a transverse sectional view through the carrier and running board, showing the preferred means for securing it to the board.

In the drawing, 2 represents the running board of an automobile.

3 represents brackets, U-shaped, substantially, in cross section, each having an upper arm 4 to rest upon the upper surface of the running board parallel therewith and with the lower arm. The loop of the bracket is seated against the outer edge of the running board. The bracket is preferably made angular in cross section and the horizontal flange of the arm 5 is provided with thumb screws 6 which engage the under surface of the running board and clamp the bracket securely thereon. Each bracket also has a vertical flange between which the frames of the luggage carrier are secured and which I will now describe in detail.

An outer movable frame is provided, rectangular, preferably, in form and composed of an inner angle bar rail 7 and end rails 8 and an outer flat bar 9 that is secured at

its ends to the horizontal flanges of the end rails by means hereinafter described. Cross bars 10 are riveted to the rail 9 and to the horizontal flange of the rail 7 at suitable intervals. The inner movable frame of the carrier consists of an outer angle bar rail 11, an inner flat rail 12 and end bars 13. Cross bars 14 are also provided, connecting the side rails of the outer frame. The rail 12 is seated at the ends on the horizontal flanges of the end rails 8 and slides under the cross bars 10 and is guided thereby. The rails 13 have longitudinal slots 15 therein to coincide with similar slots in the rails 8. Bolts 16 are mounted in the vertical flanges of the brackets 3 and pass through the slots 15 of corresponding flanges of the rails 8 and 13 and form guides for the rails 8 and 13 to slide on when the frames are adjusted back and forth with respect to the brackets 3 to enlarge or contract the carrier. Similar bolts 17 are mounted in the brackets, passing through a slot 17' in the end rails of the outer frame. These bolts are all preferably provided with wing nuts 18 by means of which the bolts may be tightened or loosened, as desired.

Handles 19 are provided at the ends of the carrier and secured to the vertical flanges of the brackets by the bolts 16 and 17, said bolts serving not only as a securing means for the handles but also as connections between the movable frames. I also prefer to provide loops 20 secured to the vertical flanges of the rails 7 and 11 of the frames. These handles and loops are adapted to receive straps or cords for securing the luggage in place on the carrier.

From an examination of Figs. 2 and 3 it will be noted that the brackets have broad substantial bearing surfaces on the top of the running board and also on the outer edges thereof, and the thumb screws engaging the underside of the running board clamp these brackets firmly thereon and hold them rigidly against the strain or jar incident to the running of the car over rough roads. At the same time, these bolts may be loosened and the carrier readily removed.

When the frames have been adjusted in a desired position, they can be easily and quickly locked by tightening the wing nuts 18. The frames may be made in various sizes to suit different lengths and widths of running board, and in various ways the details of construction herein shown and de-

scribed may be modified and still be within the scope of my invention.

I claim as my invention:

1. In combination, with a vehicle running board, clamps, U-shaped substantially in form, mounted to straddle said board, each having an arm seated on the upper surface of the board and extending substantially the full width of the board, a main frame seated 10 on the running board between said brackets and secured thereto, and an auxiliary frame also seated on the running board between said brackets and telescoping with said main frame.
  15. 2. A luggage carrier comprising brackets, U-shaped substantially in form and having horizontal and vertical flanges, the upper arms of said brackets having their horizontal flanges seated on the upper surface 20 of the running board and the lower arms of said brackets extending under the running board and having means for clamping them thereon, a rectangular main frame interposed between the vertical flanges of said 25 brackets, bolts for securing said vertical flanges to the end rails of said frame, and an auxiliary rectangular frame having end rails provided with slots to receive said bolts and slideable thereon to increase or decrease 30 the width of the carrier.
  35. 3. In combination with a running board, brackets secured thereon, a main frame interposed between said brackets and composed of side and end rails and cross bars connecting said side rails, an auxiliary frame also composed of side and end rails and cross bars between the side rails, the inner side rail of said auxiliary frame being beneath the cross bars of said main 40 frame and guided thereby and by the end rails of said frame.
  4. In combination with a running board,
- brackets secured thereon having vertical flanges, a main frame fitting between vertical flanges of said brackets and having end 45 rails composed of angle bars, an auxiliary frame having end rails provided with longitudinal slots, bolts passing through said vertical flanges and through the end rails of said main frame and through the slots of 50 the end rails of said auxiliary frame and on which bolts said auxiliary frame is slideable.
5. The combination, with a running board, of a luggage carrier comprising a pair of frames, rectangular in form, mounted to 55 telescope one with the other and having side and end rails and cross bars between said side rails and clamps for securing said frames to said board for relative lateral movement thereon, the side rails of said 60 frames alternating in position across the carrier.
6. The combination, with a running board, of a luggage carrier comprising a pair of frames, rectangular in form, mounted to 65 telescope one with the other and having side and end rails and clamps for securing said frames to said board for relative lateral movement thereon, said clamps having guides extending transversely of said 70 board and between which said frames are mounted to slide.
7. The combination, with a running board, of a luggage carrier comprising a pair of frames rectangular in form, each having 75 side and end rails, one of said frames fitting within the other frame and having a relative lateral movement therewith, and clamps secured to said running board and having means for guiding said frames in 80 such lateral movement.

In witness whereof, I have hereunto set my hand this 30th day of November 1915.

LE ROY O. HENDRICKS.
